UNITED STATES PATENT OFFICE.

JAMES EDWIN RUSSELL, OF ELKINS, WEST VIRGINIA.

CABINET FOR LACES, &c.

SPECIFICATION forming part of Letters Patent No. 634,589, dated October 10, 1899.

Application filed February 21, 1899. Serial No. 706,345. (No model.)

To all whom it may concern:

Be it known that I, JAMES EDWIN RUSSELL, a citizen of the United States, residing at Elkins, in the county of Randolph and State of 5 West Virginia, have invented certain new and useful Improvements in Cabinets for Ribbons, Laces, and Like Narrow Goods, of which the following is a specification.

My invention relates to cabinets for holding 10 and displaying narrow goods—such as ribbons, laces, edgings, and the like—and has for its object to improve such cabinets in several particulars, as will be hereinafter pointed out.

Figure 1 of the drawings is a perspective 15 view of a cabinet embodying my improvements. Fig. 2 is a vertical longitudinal section. Fig. 3 is a transverse section. Fig. 4 is a perspective view of the top of the cabinet inverted and illustrating the means for 20 filling a spool. Figs. 5, 6, and 7 are detail views enlarged. Fig. 8 is a longitudinal sectional view of a spool made in two parts telescopically fitting together.

The cabinet (designated as a whole by A) 25 is preferably mounted on a base B, in which is a drawer or drawers b, and is supported upon a vertically-disposed pivot c, so that it may be revolved thereupon.

The cabinet is preferably made double— 30 that is, it is arranged to support the spools which carry the goods upon either side of a central partition D. When the case is made single, the partition serves as the back of the case, as will be understood.

35 E E represent the ends of the case. They are entirely closed, thus adding to the neat and finished appearance of the cabinet and serving to tightly close it against the admission of dust and dirt, in this respect differing 40 from cabinets of this kind as heretofore made, wherein the ends are perforated for the mounting of the spool-carrying shafts.

45 F F represent the spool-supporting shafts, and G the spools upon which the goods are wound. The shafts are mounted within the cabinet so that they will not turn as the spools are rotated thereupon during the act of unwinding the goods. This I prefer to accomplish by squaring the ends of the shafts, 50 as at f, and mounting these ends in recesses

formed in bearing blocks or pieces H, secured to the inner faces of the end pieces E. Instead of having the shafts extend entirely across the cabinet I prefer to subdivide the interior compartment of the cabinet by transverse partitions I, one being represented on each side of the partition D.

55 The spools G, which are preferably formed of paper, though other material may be used in their formation, have a central tubular portion g and end flanges g', and they fit loosely upon the shafts F, so as to be free to turn thereon. The contiguous spools when in place upon the shafts are separated from each other by washers J or other suitable 60 spacing devices held so as not to turn upon the shafts, and thereby preventing the motion of one spool from being communicated to its neighbor. The shafts may be slightly eccentric in cross-section and the washers 65 provided with apertures of corresponding shape and size, or the shafts may be circular and provided with a longitudinal groove and the washers provided with projections or spurs j, which fits such groove, or other means may be 70 devised to prevent the washers from turning on the shafts.

The sides of the cabinet are provided with removable sections or doors K, which may be taken off to permit access to the compartments of the cabinet or fastened in place to close the same. When the doors are in place, there are narrow slits or openings L, through 75 which the goods extend.

80 It will be seen that whenever a spool becomes empty, and for that reason or for any other it becomes desirable to remove it from its shaft, the door of the compartment of that particular spool is opened and the shaft of the spool removed from the case or cabinet, 85 which can be easily done by lifting it from its bearings. The desired spool may then be taken from the shaft and another put in its place, the drawer B being used to contain 90 filled spools, if desired, or the shaft returned 95 without another spool being placed thereon to take the place of the one removed.

100 In ribbon or lace cases as heretofore made it has been the custom to provide for filling the spools while upon the same shafts as those

used for supporting them for display. There are several objections to this arrangement, all of which I avoid by providing a simple means for winding the spools which is entirely independent of the supporting-shafts F.

M represents the top of the case or cabinet. It is removable and fits tightly upon the ends E, so as to give a finished appearance to the cabinet and at the same time to tightly close to the upper part thereof. The top is so shaped as to form one or more compartments, as clearly represented in the drawings, and in the top there is mounted a shaft N, extending through one of the end pieces m of the top and shaped at its outer end to receive a crank-handle O, by which it may be turned. This shaft is removable, so that the spools G may be easily placed thereon and removed therefrom. It may be mounted in any suitable manner and arranged either to remain permanently in place or to be put in place only when it is desired to use it. This shaft is preferably smaller in size than the shafts F and has mounted thereon a wedge-piece P, which is fitted to the shaft so as to turn therewith and yet is preferably free to slide upon the shaft. This wedge-piece is preferably formed of a cylindrical portion p and a tapering finger p', which lies close to the face of the shaft. When the spool is to be filled, the top is inverted, the shaft N removed, and the spool slid upon that shaft and the wedge P made to engage therewith, the finger p' entering the tubular part g of the spool and so uniting the spool to the shaft that they will turn together. The wedge P might be inte-

gral with or securely fastened to the shaft, if preferred.

The spools may be made in two parts telescopically fitting together, as represented in Fig. 8, so that they may be adjusted to accommodate goods of different widths.

The cabinets may be made of any size and shape desired, and if thought desirable may be provided with glass outside doors. A convenient-sized cabinet is one containing six shafts each nine inches long on each side of the partition B.

What I claim is—

1. A cabinet for ribbons and like narrow goods having a removable top, a winding-shaft therein, and spool-supporting shafts in the body of the cabinet, substantially as set forth.

2. A cabinet for ribbons and like narrow goods, having a removable top, a series of removable spool-supporting shafts mounted in the body of the cabinet, and a winding-shaft provided with means for securing a spool thereto and supported in bearings in the said removable top, substantially as set forth.

3. The combination of a shaft and a device for securing thereto a spool, consisting of a substantially cylindrical portion, p, fitted to the shaft so as to turn therewith, and a tapering finger, p', projecting from the said cylindrical portion substantially parallel with the shaft, substantially as set forth.

JAMES EDWIN RUSSELL.
